UNITED STATES PATENT OFFICE.

GEORGE W. STEDING, OF BOWLING GREEN, MISSOURI.

DESIGN FOR KNIVES.

SPECIFICATION forming part of Design No. 20,334, dated November 18, 1890.

Application filed October 22, 1890. Serial No. 363,988. Term of patent 14 years.

To all whom it may concern:

Be it known that I, GEORGE W. STEDING, a citizen of the United States, and a resident of Bowling Green, in the county of Pike and 5 State of Missouri, have invented certain new and useful Improvements in Designs for Knives; and I do declare the following to be a full, clear, and exact description of the invention, such as will enable others skilled 10 in the art to which it appertains to make and use the same, reference being had to the accompanying drawing, and to letters of reference marked thereon, which form a part of this specification.

15 The figure of the drawing is a representation of the invention in perspective.

This invention has relation to designs for knives used in making incisions in the snouts of hogs to prevent the latter from rooting; 20 and it consists in the novel form and configuration shown and described.

In the accompanying drawing, the letter A designates the knife, having a rearward-extending tongue B, with parallel lateral margins a and perforation c. The tongue is 25 integral with a transverse rectangular forward plate d in the same plane with the said

tongue, said plate having downward and inward inclined tapering angular wings E, forming at their junction therewith the internal 30 acute angles e. The plate d is slightly curved or depressed above, as at f, near its forward edge, which is beveled on the inside to an acute edge. At the intersection with the tongue B the plate d extends laterally therefrom in opposite directions, thereby forming shoulders k, which cause the plate d and tongue B conjointly to assume the form of the letter T. The rear borders m of the wings E are inclined from above downward, 40 as at n, extending to the lower horizontal border o of the said wings, whereby the latter have the general form of a right-angled triangle.

What I claim is—

The design for a knife having the form and configuration substantially as herein shown and described.

In testimony whereof I affix my signature in presence of two witnesses.

GEO. W. STEDING.
